MOUNT FOR CALENDAR PAD, WRITING
IMPLEMENT AND MATERIALS

Gordon E. Nichols, Middleboro, Mass., assignor to Winthrop-Atkins Co., Inc., Middleboro, Mass., a corporation of Massachusetts

Filed Aug. 19, 1963, Ser. No. 302,946
10 Claims. (Cl. 248—465)

This invention relates to a supporting structure for calendar pads, photographs, writing implements, and the like, and is designed especially to be placed on a desk, table, or the like.

The principal objects of the invention are to provide a structure of the foregoing kind which is of extremely simple one-piece construction; which can be set up easily in either one of two different positions; which is adapted not only to support calendar pads, photographs and advertising, but also writing implements and materials; and which is durable and can be used as a base to support other structures in an inclined position.

As herein illustrated, the structure comprises a flat rigid panel having a leg comprised of parts connected at their proximal ends to the panel along spaced parallel lines transversely of the panel for pivotal movement relative thereto, and at their distal ends to each other. One of the parts has a hinge intermediate its ends spaced from and parallel to the hinge connecting the distal ends of the parts which permits bending of the portions of the one part at opposite sides of the hinge, and there is a brace operative, on the one hand, to hold the portions in a common plane and, on the other hand, to permit them to bend relative to each other to enable pivotal movement of the parts at their proximal ends to positions substantially parallel to the panel. The brace is integral with the portion of the hinged part situated between the hinge and the distal end of the part and is cut out of the portion of the hinged part situated between the hinge and the proximal end thereof. A shoulder on the panel is operative, by engagement of the brace therewith, to hold the hinged portions of the one part in a common plane convergent with the plane of the other part. The converging parts provide a wedge-shaped pocket at one side of the panel and the panel contains openings through it affording access to the pocket.

The invention will now be described in greater detail with reference to the accompanying drawings wherein:

FIG. 1 is a front elevation of the structure disclosed in one of two possible positions;

FIG. 2 is an end elevation of FIG. 1;

FIG. 3 is a vertical section, to much larger scale, taken on the line 3—3 of FIG. 1, showing the leg partly collapsed;

FIG. 4 is an end elevation of the structure disposed in the other of its two possible positions; and

FIG. 5 is a rear view of FIG. 4.

Referring to the drawings, the structure comprises a flat rigid panel 12 having at one side rearwardly converging parts 14 and 16 which collectively provide a leg 10 adapted to support the panel in an inclined position. The parts 14 and 16 are connected at their proximal ends to the panel 12 by hinges 22 and 24, the hinges being situated in spaced parallel relation to each other and to the top and bottom edges of the panel. The distal ends of the parts are pivotally connected by a hinge 26. The part 16 has intermediate its ends, near its distal end, transversely spaced hinges 28—28 (FIG. 5), spaced from and parallel to the hinge 26, which permit bending the portions 16a and 16b of the part 16 at opposite sides of the hinges 28—28 relative to each other and hence pivotal movement of the parts 14 and 16 about the hinges 22 and 24

relative to the panel in to substantially parallel relation thereto. A brace 18 cut out of the portion 16a and comprising an integral rigid extension of the portion 16b is operative, when held in the plane of the portion 16a, to prevent bending of the portions relative to each other and thereby to hold the leg in operative position. The portion 16b, with which the brace is integral, constitutes a connecting or linking part between the parts 14 and 16a. A shoulder 30 (FIG. 3), at the rear side of the panel, is operative to hold the brace in the plane of the portion 16a. When the brace is disengaged from the shoulder, as previously stated, the parts 14 and 16 may be pivoted relative to the panel, such pivotal movement being shown in dotted lines in FIG. 3.

15 The converging parts 14 and 16 provides, at the rear of the panel 12, a wedge-shaped pocket, and the panel 12 is provided with openings 34 and 36 affording access to this pocket and through which may be thrust writing implements and/or writing materials for support. A calendar pad c may be attached to the face of the panel 12 at one side of the openings and advertising matter may be applied to the face of the panel at the other.

20 As constructed, the structure is made of a single sheet of paperboard or the like folded at 32 (FIG. 3) to provide the front panel 12 and an extension 12x at the rear side of sufficient length to provide for the parts 14 and 16 and the brace 18. The extension is secured to the rear side of the panel 12 above and below the leg, for example, by staples or adhesive (not shown).

25 30 The hinges are made by covering the adjacent edges of the parts with paper in customary fashion as shown in Patent No. 2,880,948, dated April 7, 1959 (FIG. 6).

The structure shown in FIGS. 1 and 2 is disposed so as to incline rearwardly at a relatively flat angle with respect to the horizontal; however, as shown in FIG. 4, it may be disposed at a relatively steep angle to provide a distinctively different appearing mount.

35 40 In either of its positions, the structure may be the end product itself or may constitute a base for a facing structure, for example a frame for a photograph or the like.

The blank of which the structure is made is shown in FIG. 5 with the parts making it up identified with reference characters corresponding to the parts applied thereto in the foregoing description.

45 It should be understood that the present disclosure is for the purpose of illustration only and that this invention includes all modifications and equivalents which fall within the scope of the appended claims.

I claim:

50 1. A structure comprising a flat rigid panel, parts hinged at one end to the panel in spaced parallel relation, a brace, a part comprising an integral rigid extension of one end of the brace to which the distal ends of the parts are hinged in spaced parallel relation, and a shoulder on the panel operative, by engagement of the other end of the brace therewith, to hold one of the parts and the brace to which its distal end is hinged in a common plane convergent with the other part.

55 60 2. A structure comprising a flat rigid panel, parts of different length extending from the panel at an angle thereto, said parts being connected to the panel along spaced parallel lines transversely of the panel for pivotal movement relative thereto, a linking part narrower than the space between the proximal ends of the parts, hinge means connecting the distal ends of the parts to the linking part, a brace comprising an integral rigid extension at one end of the linking part, and means on the panel operative, by engagement of the distal end of the brace therewith, to hold one of the parts, the linking part and the brace in a common plane convergent with the other part and immobilizing the hinge means connecting the parts.

65 70 75 80 85 90 95

3. A structure comprising a flat rigid panel, parts connected to one side of the panel along spaced parallel lines transversely of the panel for pivotal movement relative thereto and to each other, said parts being of different length, a linking part to which the distal ends of the parts are hingedly connected, a brace comprising an integral rigid extension of the linking part at the edge hinged to the part of shorter length, and means on the panel operative, by engagement of the distal end of the brace, to hold the brace substantially in the plane of the shorter part.

4. A structure comprising a flat rigid panel, parts of different lengths connected at their proximal ends to one side of the panel along spaced parallel lines for pivotal movement, a brace, hinges at one end and intermediate the ends of the brace to which the distal ends of the parts are connected along spaced parallel lines, with the hinge of the part of greater length connected to the end of the brace and the hinge of the part of lesser length connected to the brace intermediate its ends, and a shoulder on the panel with which the opposite end of the brace is engaged operative to hold the brace in the plane of one of the parts, said brace being disengageable from said shoulder to permit bending the brace relative to said part of greater length at the hinge connecting the two and hence pivoting of the parts at their proximal ends relative to the panel into position substantially parallel to the panel.

5. A structure comprising a flat rigid panel having top, bottom and side edges, parts connected at their proximal ends to one side of said panel in spaced parallel relation to each other and to the top and bottom edges of the panel, said parts being of different length and converging rearwardly from the panel, a connecting part, hinge means joining the connecting part at its edges to the distal ends of the parts and normally situated in the plane of the shorter part, a brace comprising an integral rigid extension of the connecting part at the edge connected to the shorter part operative, by engagement with the panel, to hold the connecting part and the shorter part rigidly in a common plane which converges with the longer part at the hinge joining the longer part to the connecting part, said brace being disengageable to permit the connecting part to bend relative to the shorter part, and the parts to pivot at their proximal ends relative to the panel.

6. A structure comprising a flat rigid panel, parts connected at their proximal ends to the panel in spaced parallel relation to each other and to the top and bottom edges of the panel, a hinge connecting said parts at their distal ends and providing at said side of the panel a wedge-shaped pocket, said panel containing openings through it affording access to the pocket, a hinge near the distal end of one of the parts parallel to the hinge connecting the distal ends of said parts, said hinge dividing said one part into portions adapted to bend at said hinge, and a brace comprising an integral rigid extension of the part connected to said other part and operative, by engagement with the panel, to hold the portions of said one part at opposite sides of said second-named hinge in a common plane, said brace being disengageable to permit bending and pivotal movement of the parts about their proximal ends into substantially parallel relation to the panel.

7. A structure comprising a flat rigid panel, a leg at one side of the panel comprising parts connected at their proximal ends to the panel in spaced parallel relation, said parts converging at their distal ends, a hinge connecting the distal ends of the parts and being hingedly connected to each other, a hinge near the distal end of one of the parts spaced from and parallel to the hinge connect-

ing the distal ends of the parts, said hinge dividing said one part into two limbs and a brace integral with one of the limbs, said brace being operative, on the one hand, when supported in the plane of the proximal end of the one part, to hold the portions of the one part at opposite sides of the hinge in a common plane and, on the other hand, when unsupported to permit said portions to bend relative to each other.

8. A structure comprising a flat rigid panel, a leg at one side of the panel comprising parts connected at their proximal ends to the panel in spaced parallel relation, said parts converging at their distal ends, a hinge connecting the distal ends of said parts to each other, a pair of transversely spaced hinges spaced from and parallel to said first-named hinge, a brace integral with the portion of the part situated between said spaced hinges and said first-named hinge, said brace being cut out of the portion of the part between said spaced hinges and the proximal end of the part and being operative, when held in the plane of the part, to prevent bending of the portions of the part at opposite sides of said spaced hinges and, when released, to permit bending of the portions, and means for releasably holding said brace in the plane of the parts.

9. A structure comprising a flat rigid panel, a leg extending from one side of the panel comprising straight parts pivotally connected at one end in spaced parallel relation to the panel, said parts converging uniformly throughout their length toward each other and being connected at their convergent distal ends to each other, a hinge in one of said parts intermediate its ends dividing said one part into proximal and distal limbs which may be bent relative to each other, the distal limb of said one part being connected to the other part, and a brace integral with the distal limb of said one part operative, when supported in the plane of the proximal limb of said one part, to hold said hinge immobile, and means on the panel with which the proximal end of the brace is adapted to be engaged for support in a common plane with said one part.

10. A structure comprising a flat rigid panel, a leg extending from one side of the panel comprising parts pivotally connected at one end in spaced parallel relation to the panel and at their distal ends to each other, one of said parts containing a hinge intermediate its ends upon which portions of said one part at opposite sides of the hinge may be bent relative to each other, a brace comprising an integral rigid extension of one portion and a shoulder on the panel operative, by engagement with an end of the brace, to hold the brace and said one portion with which it is integral in the plane of said other portion.
